PROCESS AND DEVICE FOR TWISTING THREADS OR FILAMENTS

Michel Lattion, Morges, Switzerland, assignor to Pag Patentgesellschaft A. G., Zurich, Switzerland

Application October 31, 1951, Serial No. 254,044

Claims priority, application Switzerland November 4, 1950

10 Claims. (Cl. 57—62)

The present invention relates to a process and a device for the twisting or doubling of threads or filaments of any kind.

The process is characterized by the fact that the thread or filament to be twisted is led freely from the creel bobbin downwards through the bore of a vertical spindle and, on its emergence from the lower end of the said bore, upwards against over pulleys to a winding bobbin arranged above the upper end of the bored spindle and is wound upon the said bobbin.

The device for the performance of the twisting process in accordance with the invention possesses a vertical spindle with a bore extending from end to end thereof, which spindle is so held elastically and in a vertical position to a table by a clamping device that it can align itself to its ideal axis of rotation.

The object of the invention is illustrated in the drawing in the form of two preferred embodiments.

Fig. 1 is a sectional view of a device with a rotating spindle, and

Fig. 2 is a sectional view of a device with a stationary spindle.

The vertical spindle 1 is provided with a bore 2 extending throughout the length of the said spindle, the shoulders of which bore at either end thereof are rounded. The thread 3 to be twisted is guided downwards from the creel bobbin 4 through the said bore and is, on its emergence from the lower end of the said bore, taken over pulleys 5, 6, which are secured to the table slab 7 by means of straps 8, vertically upwards over a pulley 9, a deflecting bar 10 and a thread guide 11, to the winding bobbin 12, which is driven by the roller 13.

In Fig. 1 the spindle 1 is rotatably mounted in a ball bearing 14 and a roller bearing 15 both of which embrace the said spindle. The said bearings are held in the two ends of a bearing sleeve 16 having a flange 17. On the inner face of the flange 17 are two elastic discs or collars 18 by which the bearing sleeve 16 bears the table slab 7 and by which it is clamped thereto. On the lower face of the lower disc or collar 18 is fitted a covering disc or collar 20 against which is braced one end of a helical spring 21, whilst nuts 22 press against the other end of the said helical spring 21, said nuts being adjustable on a screw thread 23 disposed on the lower end of the bearing sleeve 16, so that the bearing sleeve 16 can be elastically clamped more or less strongly to the table slab 7. Screwed on to the extreme end of the bearing sleeve 16 is a threaded disc 24 against which a threaded cap 25 is screwed which closes the end of the bearing sleeve and through the crown of which only the end of the spindle projects. On the cap is an eye or lug 26 with a spring-loaded plunger 27 by means of which the spindle can be braked. The spindle 1 projects freely from the upper end of the bearing sleeve 16, and on the same, immediately above the roller bearing 15, is fitted the pulley or wharve 28 over whose lower part runs portion of the drive belt, not shown, whilst on the upper face 29 of the said pulley or wharve the creel

2

bobbin, likewise not shown, is mounted. Circlips 30 serve to secure the ball and roller bearings on the spindle 1 in the bore 31 of the bearing sleeve 16, whilst a bore 32 is provided for purposes of lubrication.

5 In the embodiment of Fig. 2, a flange 33 is rigidly affixed to the bored spindle 1, on the lower face of which flange elastic discs or collars 18, between which the table slab 7 is held, are again disposed. The lower portion of the spindle 1 is provided with a screw thread on which 10 two nuts 34 and a disc or washer 35 are fitted which press against a helical spring 36 which in turn is braced against the metal disc or collar 20 in such a way that the spindle can be elastically clamped to the table slab 7. A sleeve 37 is rotatably mounted on the spindle 1 above the flange 33, which sleeve has at its lower end a thickened portion in which the roller bearing 37' is mounted. The cylindrical portion located above the bearing serves as a belt pulley or wharve for the drive of the spindle. Above this portion is located a collar 38 and above this again an extension 39 on which is mounted a tube 40 which carries the ball bearing 41 at its upper end. Below and above the ball bearing 41 are inserted pans 42 to accommodate felt seals for the ball bearing, and the upper end of the tube 40 is sealed by 25 a plug 43 through the crown of which the upper end of the spindle projects. The spool 44 is fitted over the tube 40, and bears at the bottom against the edge of the collar 38.

The thread or filament to be twisted is, in the manner 30 already described, guided from the bobbin 4 through the bore 2 of the spindle to the pulley 5 at the lower end of the spindle and thence upwards to the winding bobbin.

What I claim is:

1. An apparatus for twisting threads or the like which 35 comprises a vertical hollow tube, a sleeve surrounding the tube mounted for rotation about the axis of the tube, means for rotating said sleeve, a creel bobbin mounted upon said sleeve to rotate therewith, winding means, and means including a fixed pulley mounted directly below the tube but spaced therefrom for guiding threads from the bottom end of the tube to the winding means, the space between the lower end of the tube and the fixed pulley being unobstructed, whereby said thread to be twisted extends from the creel bobbin outwardly freely 45 in a balloon fashion, thence directly into the tube, through the tube and over said fixed pulley to said winding means, and whereby twist is imparted to the whole length of the thread between the upper end of the tube and the fixed pulley.

2. In an apparatus as claimed in claim 1, means for 50 resiliently mounting said tube upon a fixed base comprising a second sleeve surrounding the tube, said second sleeve extending at least partially into the first sleeve, said second sleeve comprising bearing means adjacent said tube to permit the rotation of said tube within said second sleeve.

3. An apparatus for twisting threads or the like, comprising a vertically positioned hollow member, a creel bobbin, journaling means for mounting said bobbin for rotation about the longitudinal axis of said member, means for imparting rotation to said bobbin, winding means, and means including a fixed pulley located directly below said member but spaced therefrom for guiding threads from the bottom end of said member to the winding means, the space between the lower end of the hollow member and the fixed pulley being unobstructed, whereby the thread to be twisted extends from the creel bobbin outwardly freely in a balloon fashion, thence directly into the hollow space of the member, through the hollow space, and over the pulley to said winding means, and whereby twist is imparted to the whole length of

the thread between the upper end of the hollow member and the fixed pulley.

4. An apparatus for twisting threads or the like, comprising a vertically positioned hollow tube, a resiliently mounted sleeve surrounding at least a portion of said tube, bearings within said sleeve for journaling said tube for rotation within said sleeve, means for imparting a rotary motion to said tube about its longitudinal axis, a creel bobbin mounted concentric with said tube, winding means, and means including a fixed pulley mounted directly below said tube but spaced therefrom for guiding threads from the bottom of the tube to the winding means, the space between the lower end of the tube and the fixed pulley being unobstructed, whereby the thread to be twisted extends from the creel bobbin outwardly freely in a balloon fashion, thence directly into the hollow space of the tube, through the hollow space and over the pulley to said winding means, and whereby twist is imparted to the whole length of the thread between the upper end of the tube and the fixed pulley.

5. In an apparatus for twisting threads or the like as in claim 4, wherein said resiliently mounted sleeve comprises in its upper portion a flange, a flat metal disc surrounding said sleeve below said flange, a resilient disc having two spaced flanges surrounding said sleeve between said metal disc and said sleeve flange, an annular fixed plate positioned between said spaced flanges, and spring means for urging said flat metal disc upwardly toward the lower surface of said sleeve flange.

6. An apparatus for twisting threads or the like, comprising a vertically disposed hollow tube, a resiliently mounted first sleeve concentrically surrounding at least a portion of said tube, bearings within said first sleeve for rotatably journaling said tube about its longitudinal axis, a second sleeve mounted concentric with said tube and said first sleeve and secured to the tube, said second sleeve surrounding the upper portion of said first sleeve, a creel bobbin concentric with said tube and mounted upon the upper end of said second sleeve, and means for imparting rotation to said second sleeve, winding means, and means including a fixed pulley positioned directly below said tube but spaced therefrom for guiding threads from the bottom of the tube to the winding means, the space between the lower end of the tube and the fixed pulley being unobstructed, whereby the thread to be twisted extends from the creel bobbin outwardly freely in a balloon fashion, thence directly into the hollow space of the tube, through the hollow space and over the pulley to said winding means, and whereby twist is imparted to the whole length of the thread between the upper end of the tube and the fixed pulley.

7. A process for twisting threads or the like which comprises the steps of unwinding a thread in a balloon

fashion from a rotating creel bobbin having its axis of rotation in a substantially vertical plane, passing said thread directly through the upper end of and into a hollow tube mounted concentrically with said creel bobbin, withdrawing said thread from the lower end of said tube, passing the thread over at least one pulley whose position relative to said tube is fixed, imparting twist to the whole length of the thread between the upper end of the tube and the fixed pulley, and winding the thread upon a second bobbin.

8. In an apparatus for twisting threads or the like, a base, a vertical hollow tube extending through said base, a sleeve surrounding the tube mounted for rotation about the axis of the tube, means for rotating said sleeve, a second sleeve surrounding the tube, said second sleeve extending at least partly into the first sleeve, said second sleeve comprising bearing means adjacent said tube to permit the rotation of said tube within said second sleeve, and a creel bobbin mounted upon said first sleeve to rotate therewith.

9. In an apparatus for twisting threads or the like, a vertically positioned hollow tube, a resiliently mounted sleeve surrounding at least a portion of said tube, bearings within said sleeve for journaling said tube for rotation within said sleeve, means for imparting a rotary motion to said tube about its longitudinal axis, the lower end of said tube being unobstructed, and a creel bobbin mounted concentric with said tube.

10. In an apparatus for twisting threads or the like, as claimed in claim 9, said resiliently mounted sleeve comprising in its upper portion a flange, a flat metal disc surrounding said sleeve below said flange, a resilient disc having two spaced flanges surrounding said sleeve between said metal disc and said sleeve flange, an annular fixed plate positioned between said spaced flanges, and spring means for urging said flat metal disc upwardly toward the lower surface of said sleeve flange.
